CONTROL MECHANISM FOR THE WRINGER ROLLS OF A WASHING MACHINE

Peter Eduard Geldhof, Syracuse, N. Y., assignor to Easy Washing Machine Corporation, Syracuse, N. Y., a corporation of Delaware

Application October 20, 1933, Serial No. 694,428

20 Claims. (Cl. 68—32)

My invention relates to control mechanism for the wringer rolls of a washing machine.

An object of my invention is to provide means whereby the starting, stopping and reversing of the rolls may be accomplished with but slight physical effort.

Another object of my invention is to provide means whereby, upon operation of the usual safety device associated with the wringer rolls, the power of the drive shaft is automatically employed to disengage the driving mechanism for the rolls.

A further object of my invention is to provide a push button control for the wringer rolls of a washing machine whereby the rolls may be controlled from both sides of the machine.

Another object of my invention is the provision of a wringer roll driving and reversing unit which may be mounted on a washing machine, driven therefrom and swung to any position with respect thereto, the unit including a driving clutch thrown by the power of the drive shaft into engagement with either of a pair of resiliently mounted clutch elements, the assembly being so arranged that the entire driving and reversing mechanism is mounted in a compact unit in a convenient position for operation.

My invention further contemplates the provision of a clutch element thrown by power into and out of engagement with the clutch elements of a roll driving and reversing mechanism whereby the rolls may be controlled with little physical effort from either side of the machine and whereby the operation of the usual safety device for the rolls operates to stop the rotation of the rolls automatically.

Other objects and advantages will be more apparent from the following description, taken in connection with the accompanying drawings, in which:

Figure 1 is a side elevation showing the wringer rolls and the control means therefor.

Figure 2 is a view taken on line 2—2 of Figure 1.

Figure 3 is a side elevation partially in section showing the construction of the safety device and control mechanism for the wringer rolls.

Figure 4 is a view taken on line 4—4 of Figure 3.

Figure 5 is a view taken on the line 5—5 of Figure 3.

Figure 6 is a view taken on the line 6—6 of Figure 3.

Figure 7 is a perspective view showing the interior casing and relation of parts of the wringer roll safety device.

Figure 8 is a view taken on line 8—8 of Figure 5.

Figure 9 is a view taken on line 9—9 of Figure 8.

Figure 10 is a view similar to Figure 2 with the push button control arranged so that it is operable on either side of the wringer rolls.

Figure 11 is a view taken on line 11—11 of 5 Figure 10.

Figure 12 is a perspective view showing the construction of a modified form of driving clutch adapted for use in my control mechanism.

In general, as shown in Figure 1, the wringer 10 roll structure and control mechanism therefor comprise a supporting tube 11 mounted on the washing machine in any usual and well-known manner and adapted to receive and support a hollow boss 12 depending from a casing 13 enclosing and supporting the roll driving and reversing mechanism. A drive shaft 14 extends upwardly concentric with the supporting tube 11 and is driven from the driving mechanism of the washing machine in any usual manner well-known in the art to which this invention applies. 20

The drive shaft 14 is slotted at its upper extremity to receive pins 16 on the lower end of a drive shaft 17 so that the shafts 14 and 17 are driven together. A spring-pressed plunger 15 manually operable by a handle 15' is mounted in the depending boss 12 and is selectively engageable with any one of a plurality of apertures 20 formed circumferentially of the supporting tube 11. With this construction the entire wringer assembly together with the casing 13, may be removed from the supporting tube 11 by a vertical lift or may be swung about the axis of the supporting tube 11 so as to be moved with relation to the tub of the washing machine into any desired position. As shown more clearly in Figures 2 and 3, the drive shaft 17 projects upwardly into the casing 13 and has bearing supports therein at 18 and 19. The shaft 17 is supported against longitudinal displacement by a set screw 21, the end 40 of which is fitted into a recess 23 formed in the upper end of the shaft 17. 30

A driving clutch element 24, mounted on and keyed to the shaft 17 so as to be continuously rotated thereby, is longitudinally shiftable into engagement with either of a pair of driven clutch elements 26 and 27. The driving clutch element 24 is retained in a desired one of a plurality of positions by a spring-pressed ball 28 which, when the clutch is shifted, rides into any one of a 50 plurality of apertures 29 formed in the driving clutch. The driven clutch elements are splined respectively as indicated at 31 to a pair of beveled reversing gears 32 and 33. A spring 34 is mounted in a hollow annular space formed between each 55

of the driven clutch elements and the gears 32 and 33 and serves to urge each of the driven clutch elements in a direction towards the driving clutch, each of the springs being seated on a shoulder 36 formed respectively in the internal bore of the gears 32 and 33. A retaining ring 37 seats in a groove formed on the outer periphery of the driven clutch elements 26 and 27, contacts with the splines and limits the longitudinal 5 placement of the driven clutch elements in a direction towards the driving clutch.

The gears 32 and 33 mesh with a beveled ring gear 41 and the rotation of the driving clutch 24 is in a direction such that engagement of said element with the driven clutch element 33 rotates the ring gear 41 in a clockwise direction, as viewed in Figure 2, so as to drive the rolls in a direction away from the operator as viewed in Figures 1 and 3. The beveled gear 41 has formed on its rear face a hollow outwardly extending boss 42 suitably supported in the casing 13 and into which projects a flexible driving union 43 which forms a driving connection with the lower roll shaft 44 through pin slot connections 47 and 48. The upper roll 49 is driven from the lower roll through a pair of gears 50 indicated in Figure 6 mounted on the opposite end of the rolls.

I have provided, as shown more clearly in Figures 2, 3 and 8, means for utilizing the power of the drive shaft 17 to shift the driving clutch element 24 into engagement with either of the driven clutch elements 26 and 27 or from either of said positions into a neutral position. On the periphery of the driving clutch, preferably integral therewith, are a pair of cams 52 and 53 formed in a position and manner such that upon selective movement of a plurality of control plungers 54, 55, and 56 into engagement with the cam elements 52 and 53, the driving clutch is 30 cammed by the power of the drive shaft into a position to engage the desired driven clutch element or from such engagement into a neutral position. The upper and lower plungers 54 and 56 are engageable respectively with the upper and lower side surfaces of the cam elements 52 and 53 while the plunger 55 is engageable with the inner side surfaces of both cam elements 35 depending upon the position of the driving clutch.

The control plungers 54, 55, and 56 are mounted 50 for sliding movement in a plurality of guide openings bored in a control housing 58 formed as part of the casing 13 and are connected to finger-operated push button controls 60, 61 and 62 which project outside of the casing in a position for 55 convenient manipulation by the operator. It will be apparent that upon movement of the push button control 60 inwardly, the control plunger 54 is moved into engagement with the upper side surface of the cam 52 when the driving clutch 60 has moved to the proper position, and as the driving clutch continues to rotate, the power of the drive shaft positively cams the driving clutches into a position to engage the driven clutch element 27. Because the driving clutch is 65 positively shifted, in order to enable engagement of the clutch elements, the driven clutches are resiliently mounted as above described so that upon engagement of the face surfaces, the driven clutch 27 moves longitudinally of the shaft until 70 further rotation of the driving clutch enables the teeth of the elements to slide into engagement. Movement of the push button 61 actuates the control plunger 55 so as to move it into engagement with the driving clutch element midway between the cams whereby, upon rotation, the

driven clutch element is restored to a neutral position. Actuation of the lowermost push button 62 serves to cam the driving clutch upwardly into engagement with the driven clutch 26 so as to reverse the rolls and rotate them in a direction 5 towards the operator, as viewed in Figures 1 and 3.

Means are provided, whereby upon actuation of one of the push buttons, for example, the button 60, another of said push buttons is automatically moved outwardly so as to remove the particular control plunger which happens to be in operative position from such position. In this manner, the driving clutch may be shifted from one position to another upon actuation of but a 10 single button. This means comprises a pair of links 64 inter-connected between the upper and lower push buttons 60 and 62 on opposite sides thereof by pin and slot connections 66 formed respectively on the push buttons and on the links 20 64. The links 64 are pivoted, as more clearly shown in Figure 9, at substantially their mid-point to the casing 58 by means of pivot screws 67 which extend through apertures formed in the links so that upon movement of the upper button 60 inwardly, the lower button 62 through the link 64, is moved outwardly out of engagement with the driving clutch element 24.

Extending from each of the upper and lower buttons 60 and 62, as more clearly shown in Figure 2, is a projection or arm 70 which contacts with the center control button 61 for the purpose of inter-connecting the three buttons. The arms 70 together with the links 64, correlate the action of the control buttons. If, for example, the button 61 is already in operative position, upon movement of the upper button 60 inwardly into engagement with the driving clutch 30 element, the link 64 acts to move the control button 62 outwardly a distance sufficient to enable the lower arm 70, in contact with the center control button 61, to pull the control plunger 55 out of operative position with relation to the driving clutch. In this manner, the control plunger 54 is moved into engagement with the upper cam surface 52 to shift the driving clutch and during this movement, the control plunger 55 is automatically withdrawn. If either the upper or lower control plungers 54 or 56 are in engagement with the driving clutch and it is 40 desired to stop rotation of the rolls, the center button is pushed. This causes movement of the arm 70 of the push button which is not in operative position so as to move that push button inwardly a slight distance thereby rotating the link 55 64 about its pivot. The rotation of the link 64 slides the control plunger which is in engagement with the driving clutch 24 from operative to inoperative position. It will thus be apparent that the center control button 61 has two positions of movement, as indicated in the dotted and full lines, while the upper and lower control buttons 60 and 62 each have three positions, an inner position, indicated by the dotted line 72, an intermediate position indicated by the full lines in 65 60 which position the driving clutch is in neutral, and an extreme outer position indicated by the dotted line 73.

As shown more clearly in Figures 3, 4, and 6, I have shown a safety device for the wringer 70 rolls which may be of any of the various types now commonly used in connection with wringer roll mechanism, but a brief description of which is necessary although it constitutes, per se, no part of my present invention except insofar as 75

its operation is correlated with my novel power-operated control for the wringer rolls.

The wringer rolls 46 and 49 are mounted in a frame structure 75 in bearings 76 and 77 in such manner that upon release of a safety head 77, the pressure between the rolls is relieved and the upper roll 49 may be moved away from the lower roll 46. A locking link formed by a pair of arms 79 is pivoted on a cross bar 82 and extends downwardly on the outside of the roll shafts to a point near the bottom of the casing. A platform 84 is normally urged upwardly by a spring 86 and has extending upwardly therefrom a pair of members 87 behind which the lock arms 79 are positioned when the rolls are in a locked pressure engagement. On the inside of the lock arms 79 are formed a pair of cam surfaces 89 which engage a cross rod 91 secured in the wringer casing. The front longitudinal edges of the lock arms 79 are notched at 92 for the reception of a lock rod 93 mounted in the frame.

As more clearly shown in Figures 1 and 6, a release bar 94 extends across the wringer roll frame in a convenient position to be actuated by the operator. The release bar 94 has at one end pivoted thereto a link 95 which is also pivoted to the casing. A similar link 96 is pivoted to the release bar 94 on the other side and is pivoted at 97 to a member 98 which extends through a slot 99 in the casing to engage a release link 101. It will be observed, as shown in Figure 6, that a similar release bar 94, mounted on the opposite side of the roll, is connected to a release link 102 similar to the release link 101. The release links are inter-connected by a cross bar 103 and pivot on the cross rod 91 previously mentioned. The lower ends of the release links 101 and 102 contact with a member 104 pivotally mounted near the bottom of the casing, the member 104 contacting with the upper edges of the upstanding members 87 on the platform 84.

A release spring 106 is mounted in the safety head 77 by means of a threaded tension control knob 107. The ends of the spring contact with the bearings 76 on opposite sides of the casing. When the lock arms 79 are in a position such that the cross rod 93 is positioned in the notches 92 and the lower ends of the arms 79 are positioned behind the members 87, the spring 106 may be tensioned by rotating the control knob 107 and the rolls 46 and 49 brought into pressure engagement.

When the release bar 94 is pushed either accidentally or for the purpose of releasing the rolls, the link 96 is pushed toward the right, moving the member 98 in the slot formed near the top of the casing which, in turn, pushes the release links 102 about the cross rod 91 so as to rotate the release links 102 in a clockwise direction as viewed in Figure 7. Rotation of the release links 102 rotates the plate 104 in a counterclockwise direction which moves the platform 84 downwardly against the tension of the spring 86. As soon as the platform moves downwardly, the lock arms 79 are released and permitted to move past the upstanding members 87 on the platform 84 and the notches 92 move upwardly out of engagement with the lock rod 93. The spring 106 then causes the safety head and lock arms 79 to spring upwardly to release the pressure contact between the rolls.

To replace the safety head 77, as viewed in Figure 3, the left-hand end of the safety head is caught below a catch 108 and the right-hand end of the safety head is pushed down so that

the lock arms ride behind the ends of the upstanding members 87 being cammed over into such position and to locking position with respect to the lock rod 93 by the cams 89. Tension may then be put on the spring 106 which forces the rolls 46 and 49 into pressure engagement.

As shown in Figures 3, 4, and 5 a member 111 engages the platform 84 and is threaded to receive a crank arm 112 normally urged upwardly by a spring 113 secured to an outwardly extending arm 114 on the crank. The other end of the spring is secured to the casing 116. The crank arm 112 has a bearing in the casing 13 into which it extends. A U-shaped arm 118 extends around the bevel gear 33 and is fixed to the crank arm and pivoted at 119 to the other side of the casing. An integral portion 120 of the U-shaped arm 118 extends upwardly and is pivotally secured to an L-shaped arm 121. The L-shaped arm 121 is apertured at its extremity to slidably receive the center control plunger 55 which is of decreased diameter at the point of attachment to form a shoulder at 122 so that when the plunger rod 55 is out of engagement with the driving clutch element 24, the shoulder 122 is in engagement with the L-shaped arm 121.

When the release bar 94 is operated, as above described, the lock arms 79 move upwardly, enabling the spring 113 to act to rotate the crank arm 112. The rotation of the crank arm moves the L-shaped arm 121 inwardly which, through engagement with the shoulder 122, moves the control plunger inwardly to operative position to cam the driving clutch 24 by the power of the drive shaft into a neutral position.

In Figures 10 and 11 I have shown a structure in which two sets of push button controls are arranged on opposite sides of the casing 13 so that the wringer roll driving and reversing mechanism may be conveniently controlled from either side of the machine. The operation of the device is essentially the same as that above described. The additional push buttons 127, 128, and 129 on the rear side of the casing are inter-connected in a manner similar to that described in connection with push buttons 60, 61, and 62. The sets of push buttons on opposite sides of the casing are connected by a cross bar 130 curved around the driving clutch 24 and pivotally connected to the pins which retain the links 64. The center push button 128 is connected to a control plunger 131 similar to the control plunger 55, while the upper and lower push buttons 127 and 129 are centrally bored to receive members 132 fixed in the casing. The push buttons 127 and 129 do not operate directly on the driving clutch 24 merely, upon manipulation, sliding inwardly and outwardly on the members 132, their motion being transmitted through the links 64 and cross bar 130 to operate the control plungers on the opposite side of the casing. It will be observed that operation of the lower push button 129 moves the control plunger 54 into operative position, while operation of the upper push button 127 actuates the lower control plunger on the opposite side. Thus, actuation of the upper push button when the operator is standing at the front of the machine, moves the clothes fed between the rolls, in a direction away from the operator, while actuation of the upper push button at the rear of the machine, reverses the direction of the rolls, but from the operator's position at the rear of the machine, the clothes are fed in a direction away from the operator.

In Figures 3 and 8 the cams 52 and 53 are curved continuously around the surface of the

driving clutch so that when the control plunger is pushed inwardly, unless the driving clutch is in such position as to enable immediate engagement, a time interval must elapse during which the operator must maintain contact on the push button until the cam rotates into a position such that the control plunger may be pushed into engagement with the effective surface of the cam. To decrease this time interval, I have provided, as shown in Figures 10 and 12, a double acting cam so that the longest time interval which may elapse before engagement may take place, is reduced from 180 degrees rotation of the driving clutch, to 90 degrees. It will be apparent that engagement of the control plunger may be occasioned over a considerable arc of movement of the driving clutch on opposite sides thereof so that engagement of the effective surfaces is almost immediate.

It will be apparent that I have provided a driving and reversing mechanism for the wringer rolls which is power-operated and easily controlled from either side of the machine and which further automatically operates in connection with the usual wringer roll safety device to disengage the driving mechanism automatically and by power. It will further be apparent that various changes and modifications may be made in the form and relation of parts without departing from the scope of my invention, as set forth in the appended claims.

I claim:

1. The combination with a pressure releasing safety device for a roll wringing mechanism of a washing machine, of driving mechanism for rotating the rolls, said driving mechanism including a movable clutch element, means for reversing the direction of rotation of the rolls comprising a pair of driven clutch elements, power-operated means for moving said movable clutch element into engagement with either of said driven clutch elements or into a neutral position, manually operated means for selectively controlling the operation of said power-operated means, and means actuated upon release of said safety device for operating said power-operated means to throw said movable clutch to a neutral position.

2. The combination with a pressure releasing safety device for a roll wringing mechanism of a washing machine, of driving mechanism for rotating the rolls, said driving mechanism including a driving clutch element, means for reversing the direction of rotation of the rolls comprising a pair of driven clutch elements, a plurality of manually operated elements for selectively controlling the position of said driving clutch element, means associated with said driving clutch element whereby upon engagement of said manually operated means therewith, the power of said driving mechanism is utilized to throw said driving clutch element into the selected position, and means actuated upon operation of said safety device for automatically throwing one of said manually operated elements into a position such that said driving clutch element is thrown to a neutral position.

3. In a mechanism for wringing clothes, a driving shaft, a driving clutch element rotated by said driving shaft, a driven clutch element, and means including manually operated means for utilizing the power of said driving shaft to exert a positive action on said driving clutch element to throw said driving clutch element into engagement with said driven clutch element.

4. In a control mechanism for the pressure

rolls of a clothes wringer, a unitary driving and reversing mechanism for the rolls including a drive shaft, a driving clutch element and a pair of driven clutch elements, and means including manually operated means for utilizing the power of said drive shaft to throw said driving clutch element into engagement with either of said driven clutch elements.

5. In a drive mechanism for the pressure rolls of a clothes wringer, a driving shaft, a driving clutch element rotated by said shaft, a pair of resiliently mounted driven clutch elements, said driving clutch element having a plurality of cam surfaces, and a plurality of manually operated members selectively movable into engagement with said cam surfaces whereby the power of said driving shaft is utilized to throw said driving clutch element into engagement with either of said driven clutch elements.

6. In a drive mechanism for the pressure rolls of a clothes wringer, a driving shaft, a driving clutch element rotated by said shaft, a pair of driven clutch elements, means for applying the power of said driving shaft to move said driving clutch element into engagement with either of said driven clutch elements comprising a plurality of manually operated members movable into and out of operative association with said driving clutch element, and means whereby upon movement of one of said manually operated members into operative position with relation to said driving clutch element, another of said manually operated members is automatically moved out of operative position.

7. In a drive mechanism for the pressure rolls of a clothes wringer, a driving shaft, a driving clutch element rotated by said shaft, a pair of resiliently mounted driven clutch elements, means for applying the power of said driving shaft to move said driving clutch element into engagement with either of said driven clutch elements or to a neutral position comprising a plurality of manually operated members, and means interconnecting said manually operated members whereby movement of one of said manually operated members to operative position moves another of said members to inoperative position.

8. The combination in a wringer roll reversing mechanism, of a driving clutch element and a pair of driven clutch elements, and means associated with said driving clutch element for applying power thereto to throw said driving clutch element into engagement with either of said driven clutch elements or out of engagement therewith.

9. The combination in a wringer roll reversing mechanism, of a driving clutch element and a pair of driven clutch elements, a gear operatively connected to each of said driven clutch elements whereby upon movement of said driving clutch element into engagement with one of said driven clutch elements, the rolls rotate in one direction and upon movement into engagement with the other of said driven clutch elements, the rotation of the rolls is reversed, power means for rotating said driving clutch element, and means for applying said power to move said clutch into or out of engagement with either of said driven clutch elements.

10. The combination in a wringer roll reversing mechanism, of a driving clutch element and a pair of resiliently mounted driven clutch elements, a gear operatively connected to each of said driven clutch elements whereby upon movement of said driving clutch element into engage-

- ment with one of said driven clutch elements, the rolls rotate in one direction and upon movement into engagement with the other of said driven clutch elements, the rotation of the rolls 5 is reversed, power means for rotating said driving clutch element, and means for applying said power to move said driving clutch element into or out of engagement with either of said driven clutch elements comprising a plurality of manually operated members movable into and out of operative position, and means whereby upon movement of one of said manually operated members into operative position, another of said members is automatically moved out of operative 10 position.
11. In a control mechanism for the wringer rolls of a washing machine, a driving and a driven clutch element, a manually operated member having a neutral and an operative position and for use solely in moving said clutch elements into engagement and a manually operated member having a neutral and an operative position and for use solely for moving said clutch elements out of engagement, and means interconnecting said manually operated members for moving one of said manually operated members to the neutral position when the other of said members is moved to the operative position.
12. In a control mechanism for the pressure rolls of a clothes wringer, a pair of rotatable rolls, means for rotating said rolls, mechanism for controlling the operation of said rolls, a casing for housing said control mechanism, a plurality of manually operable push buttons extending into said casing, and means secured to the casing and interconnecting at least two of said push buttons whereby the movement of one of said push buttons into operative position moves the other of said push buttons out of operative position.
13. In a control mechanism for the wringer rolls of a washing machine, a pair of rotatable rolls, means for rotating said rolls, mechanism for controlling the operation of said rolls, a casing for housing said control mechanism, a plurality of manually operable members extending into said casing, means secured to the casing and inter-connecting at least two of said members whereby the movement of one of said members into operative position moves the other of said members out of operative position, and means extending from the two inter-connected members for engaging a third of said members for moving said member out of operative position upon movement of either of said inter-connected members into operative position.
14. In a control mechanism for the wringer rolls of a washing machine, a pair of rotatable rolls, means for rotating said rolls, mechanism for controlling the operation of said rolls, a casing for housing said control mechanism, a plurality of manually operated control members extending outwardly from said casing on opposite sides thereof, and means in the casing inter-connecting said members whereby the wringer rolls may be controlled from either side thereof.
15. In a control mechanism for the wringer rolls of a washing machine, a pair of rotatable rolls, means for rotating said rolls, mechanism for controlling the operation of said rolls, a casing for housing said control mechanism, roll-driving and reversing mechanism in said casing, manually operated means extending outside of said casing on opposite sides thereof, means engageable by said manually operated means for applying the power of said roll driving mecha-
- nism to cause engagement and disengagement thereof, and means extending through the casing for inter-connecting said manually operated means.
16. In a control mechanism for the pressure rolls of a clothes wringer, a unitary driving and reversing mechanism for the rolls including a drive shaft, a pair of driven clutch elements mounted on said shaft, a driving clutch element mounted on said shaft and shiftable into engagement with either of said driven clutch elements, and means including manually operated means for utilizing the power of said drive shaft to shift said driving clutch element into or out of engagement with either of said driven clutch elements.
17. In a control mechanism for the pressure rolls of a clothes wringer, means for rotating the rolls comprising a drive shaft, a toothed driving clutch element non-rotatably mounted on said shaft, a toothed driven clutch element, said driven clutch element being rotatably and resiliently mounted on said shaft whereby when the teeth of the driving clutch element are moved into contact with the teeth of the driven clutch element the resilient mounting of the driven clutch element will enable a yielding thereof whereby the teeth of the clutch elements may be moved into engagement without undue clashing.
18. In a control mechanism for the pressure rolls of a clothes wringer, means for rotating the rolls comprising a drive shaft, a toothed driving clutch element non-rotatably mounted on said shaft, a toothed driven clutch element rotatably mounted on said shaft, means for applying the power of the drive shaft to shift said driving clutch element along said shaft into engagement with said driven clutch element, said driven clutch element being resiliently mounted whereby it may yield when the faces of the teeth of the clutch elements are brought into engagement so that the teeth of the driving and driven clutch elements may be brought into registry before the driving clutch element is pushed into engagement with the teeth of the driven clutch element.
19. In a control mechanism for the pressure rolls of a clothes wringer, the combination of a unitary driving and reversing mechanism for the rolls including a constantly rotating drive shaft, a casing for the mechanism, a pair of driven clutch elements loosely mounted on said drive shaft, a driving clutch member splined to and constantly rotating with said drive shaft and having a driving clutch element on each end thereof, cam surfaces on said driving clutch member, three push buttons projecting externally of the casing and having portions thereof projecting into the casing engageable with the cam surfaces on said driving clutch member, one of said push buttons when pushed inward engaging one of said cam surfaces to urge the driving clutch member along said shaft in a direction such that one of said driving clutch elements engages a driven clutch element and the rolls are rotated in one direction, said action being accomplished by the power of the drive shaft through the continued rotation of the driving clutch member, a second of said push buttons when pushed inward engaging another of said cam surfaces to urge the driving clutch member along said shaft in the opposite direction so that the other of said driving clutch elements engages the other of said driven clutch elements and the rolls are rotated in the reverse direction, said action also being accomplished by the power of the drive shaft

through the continued rotation of the driving clutch member, and the third of said push buttons when pushed inward engaging other of said cam surfaces to withdraw the driving clutch member from either of its driving positions by the power of the drive shaft through the continued rotation of the driving clutch member.

20. In a control mechanism for the pressure rolls of a clothes wringer, the combination of a 10 unitary driving and reversing mechanism for the rolls including a constantly rotating drive shaft, a casing for the mechanism, a pair of driven clutch elements loosely mounted on said drive shaft, a driving clutch member splined to and 15 constantly rotating with said drive shaft and having a driving clutch element on each end thereof, said clutch elements being toothed and each of said driven clutch elements being yieldingly mounted so that when the driving clutch 20 elements are thrown into engagement therewith they may yield in the direction of movement of the driving clutch element to enable engagement of the clutch elements without undue clashing of clutch teeth, cam surfaces on said driving clutch member, three push buttons projecting externally of the casing and having portions thereof 25 projecting into the casing engageable with the

cam surfaces on said driving clutch member, one of said push buttons when pushed inward engaging one of said cam surfaces to urge the driving clutch member along said shaft in a direction such that one of said driving clutch elements 5 engages a driven clutch element and the rolls are rotated in one direction, said action being accomplished by the power of the drive shaft through the continued rotation of the driving clutch member, a second of said push buttons 10 when pushed inward engaging another of said cam surfaces to urge the driving clutch member along said shaft in the opposite direction so that the other of said driving clutch elements engages the other of said driven clutch elements and the 15 rolls are rotated in the reverse direction, said action also being accomplished by the power of the drive shaft through the continued rotation of the driving clutch member, and the third of said push buttons when pushed inward engaging other of said cam surfaces to withdraw the driving clutch member from either of its driving positions by the power of the drive shaft through the continued rotation of the driving clutch member. 20
